UNITED STATES PATENT OFFICE.

FRANK WM. CAMERON, OF DEPARTURE BAY, CANADA, ASSIGNOR OF ONE-HALF TO PETER M. CAMPBELL, OF SAN FRANCISCO, CALIFORNIA.

ATTACHMENT FOR PENS.

SPECIFICATION forming part of Letters Patent No. 638,556, dated December 5, 1899.

Application filed June 21, 1899. Serial No. 721,351. (No model.)

To all whom it may concern:

Be it known that I, FRANK WM. CAMERON, a citizen of the United States, residing at Departure Bay, in the Province of British Columbia and Dominion of Canada, have invented certain new and useful Improvements in Pens; and I do declare the following to be a full, clear, and exact description of the invention, such as will enable others skilled in the art to which it appertains to make and use the same.

The invention has relation to pens.

The object of the invention is to provide a pen which by dipping into the ink will take and hold sufficient ink to increase its writing capacity without replenishing, thereby saving much time which is now lost by frequent dipping of the pen.

With this object in view the invention consists in certain features of construction and combination of parts, which will be herein-after fully described and claimed.

In the accompanying drawings, Figure 1 is a perspective view of a pen illustrating my invention. Fig. 2 is a longitudinal sectional view, and Fig. 3 is a detail perspective view, of the attachment removed from the pen.

In the drawings the same reference characters indicate the same parts of the invention.

1 denotes the pen, which consists of the staff, pen-socket, and pen-point, these parts being of any well-known or approved construction and in themselves forming no part of my invention.

2 denotes the attachment, which consists of a spring-clasp 3 in the form of a longitudinal split cylinder. The forward end of this spring-clasp terminates in two parallel nibs 4,

40 which are curved slightly upward, so as to form an ink-chamber between themselves and the back of the pen-point when the attachment is slipped in place upon the pen. Immediately at the rear of these nibs is formed

a shoulder 5, so that when laying the pen 45 down the nibs of the attachment will always be supported above the surface of the desk and prevent the ink running.

In operation the pen is dipped into the well in the usual manner, and a large supply of 50 ink will be taken up and retained in the pocket formed by the back of the pen-point and the nibs of the attachment, thus enabling the writer to write from three to five hundred words without again dipping his pen. 55

The attachment is of such construction that it may be applied to any of the common forms of pens now in use and with but slight changes may be applied to any form of pen.

It will of course be understood that various changes in the form, proportion, and the minor details of construction may be resorted to without departing from the principle or sacrificing any of the advantages of this invention. 60 65

Having thus described the invention, what is claimed, and desired to be secured by Letters Patent, is—

As a new article of manufacture, an attachment for pens consisting of a clasp in the form 70 of a slotted sleeve, and provided at its forward end with integral parallel nibs which are curved upward above the plane of the sleeve and thence downward to form an arch, the points of the nibs being adapted to bear upon 75 the nibs of the pen, said sleeve being provided with an integral shoulder pressed upward upon the material and projecting above the plane of the arched nibs, substantially as and for the purpose set forth. 80

In testimony whereof I have hereunto set my hand in presence of two subscribing witnesses.

FRANK WM. CAMERON.
